UNITED STATES PATENT OFFICE.

THOMAS R. CRANE, OF HEATHSVILLE, VIRGINIA.

SPRING-TOOTHED HARROW.

SPECIFICATION forming part of Letters Patent No. 402,000, dated April 23, 1889.

Application filed December 20, 1888. Serial No. 294,141. (No model.)

To all whom it may concern:

Be it known that I, THOMAS R. CRANE, a citizen of the United States, residing at Heaths-ville, in the county of Northumberland and 5 State of Virginia, have invented certain new and useful Improvements in Spring-Toothed Harrows, of which the following is a specification.

This invention relates to an improved holder 10 or fastening for spring-teeth of harrows, and is illustrated in the accompanying drawings, in which—

Figure 1 shows a spring-tooth held by the fastening, the latter being in section and attached to a part of the harrow-frame. Figs. 15 2, 3, and 4 are detail views of the fastening. Fig. 5 is a view showing the fastening employed in attaching a spring-tooth to a drag-bar of a harrow.

20 The letter A designates a spring-tooth of any well-known form, such as are used on harrows for land. The object of this invention is to provide a holder or fastening device by which these spring-teeth may be secured 25 and may be readily adjusted, so that the point of the tooth may take into the ground more or less, as desired.

The holder comprises a box, B, and a cam-lever, C. The box has a base, d, and two 30 ears, e, attached to the base. The lever C is pivoted to the box, and has a cam-face, f, which confronts the said base d. In the present instance a bolt, g, passes through the two box-ears e, and also through the cam-lever. It will 35 thus be seen that anything placed in the space h between the cam-face f and box-base d may be tightly clamped and held.

In Fig. 1 the box B of the holder is shown bolted to a beam, I, which is part of the harrow-frame, and the top surface of the base d 40 is concave, as at d', and the shank end k of the spring-tooth is clamped by the cam-lever C. By simply tilting the cam-lever C the tooth A may be shifted one way or the other in the box B, and thereby cause the point l of 45 the tooth to take into the ground more or less.

In Fig. 5 a drag-bar, N, is shown attached to part of a harrow-frame, o, and the spring-tooth A is secured to the said drag-bar by the improved holder. In this instance the cam-lever C not only grips the shank end k of the tooth, but also grips the drag-bar N.

The lower front edge of the box-base d is beveled, as at p, to prevent it from catching the earth when being dragged along. 55

This device is simple and cheap and more convenient than any hitherto used for this purpose.

Having described my invention, I claim—

In combination with the box having a 60 base with upwardly-extending vertical ears formed integral with the base, a cam-lever pivoted between said ears, a space between the lever and base, and a spring harrow-tooth secured in said space, substantially as specified.

In testimony whereof I affix my signature in the presence of two witnesses.

THOMAS R. CRANE.
